UNITED STATES PATENT OFFICE.

JOHN A. ZUBLIN, OF LOS ANGELES, CALIFORNIA.

PUMP.

Application filed December 11, 1923. Serial No. 679,976.

To all whom it may concern:

Be it known that I, JOHN A. ZUBLIN, a citizen of the Republic of Switzerland, residing at Los Angeles, in the county of Los Angeles and State of California, have invented a new and useful Pump, of which the following is a specification.

My invention is particularly applicable to pumps used in oil wells. Such pumps are ordinarily placed at the bottom of a string of tubing near the bottom of the well and are actuated by means of sucker rods which extend upwardly through the tubing to suitable operating mechanism in the derrick. These pumps may be placed at depths of several thousand feet below the surface and it is important that they operate for long periods without removal. Petroleum oil as found in nature often contains considerable quantities of sand, silt or other abrasive material and the wear upon the plungers and pump barrels of the conventional forms of oil well pump is considerable.

It is an object of my invention to provide a plunger which will automatically take up this wear and remain tight over long periods even where considerable sand is being pumped.

Further objects and advantages will be made evident hereinafter.

Referring to the drawing which is for illustrative purposes only,

Fig. 1 is a section through the upper portion of pump embodying my invention.

Fig. 2 is a section of the lower portion of this pump.

Fig. 3 is a section on a plane represented by the line 3—3 of Fig. 2.

Fig. 4 is a section through an alternate form of pump embodying my invention.

Fig. 5 is a section through another alternate form of pump embodying my invention.

Fig. 6 is a section through still another form.

In the form of my invention illustrated in Fig. 1, I provide a coupling 11 threaded at 12 to receive the coupling of the sucker rods, not shown. The coupling 11 is threaded upon an upper hollow stem 13 which in turn

is threaded in a guide member 14, being locked therein by a lock nut 15. Also threaded in the member 14 is a lower stem 16 which has a hole 17 through its whole length as shown in Fig. 1. The lower end of the lower stem 16 is threaded in a lower guide member 20, being secured therein by a lock nut 21 having a conical seat 22 formed on its upper end. A plunger 25 seats on this seat 22 and slides upon a bearing 26 in the member 14. The member 14 has openings 27 communicating with the space inside the bearing 26. Secured in the member 20 is a plug 30 having an opening therethrough in which a garbut rod 31 is free to slide. This garbut rod has an enlarged head 32 at its upper end which is larger than the opening in the plug 30, so that the garbut rod cannot be withdrawn through the plug 30. The garbut rod extends downwardly and is threaded, as shown at 35, in a standing valve cage 36 having a conical portion 37 which is seated on a coupling 38 in which the pump barrel 39 is secured. The pump barrel 39 and the plunger 25 are ground to fit closely together. The pump barrel is secured at its upper end to the tubing of the well, not shown, from which sucker rods secured to the threaded portion 12, not shown, pass. The cage 36 has a ball valve 41 closing an opening 40 therethrough.

The method of operation of the invention is as follows:

The parts being in the position shown in Fig. 1, or at the lower end of the stroke of the plunger, the plunger is pulled upwardly, being seated on the seat 22 so that no liquid can pass downwardly therethrough. As the plunger moves upwardly, the ball 41 is lifted and the space below the plunger is filled with oil. When the plunger 25 reaches the upper end of its stroke and starts to reverse, the friction of the plunger in the barrel 39 holds the plunger stationary and allows the member 21 to move downwardly, leaving an opening between the lower end of the plunger and the seat 22. The size of this opening is regulated by adjusting the lower stem 16 up or down with relation to the seat 22. The plunger 25, as will be

noted, is made rather thin and its proportions are such and the materials from which it is constructed are such that it is expanded on the up stroke by the internal pressure thereon to fit tightly in the pump barrel 39. It will be understood that on the up stroke the weight of the column of liquid in the well exerts a pressure not only downwardly, but in all directions, against the inner 10 face of the plunger 25. This plunger being made hollow, the total pressure is considerable and it tends to expand the plunger in the pump barrel 29. Where the wear is very considerable, it is desirable to make the 15 plunger of a material having a low elastic limit so that the plunger is actually stretched and given a permanent set whenever it wears sufficiently to allow this expansion. The proportions of the plunger to produce this 20 result for different depths of well can be readily calculated, using well known formulas for the expansion of hollow cylinders under pressure.

Thus I have provided a hollow pump 25 plunger associated with means for closing its lower end during an up stroke and having a circularly continuous imperforate metallic wall engaging the pump barrel, said wall being devoid of slits or incisions 30 and capable of uniform radial expansion under the influence of the static load supported by the plunger.

In the form of the invention shown in Fig. 4, I provide a pump barrel 50 and a 35 hollow plunger 51 threaded at 52 to receive a ball cage 53. This cage has a central opening 54 therethrough which is closed by a ball 55 on the up stroke. The sucker rods 56 are secured to this cage. 40 The standing valve 57 is of the usual type having a ball 58 and an upwardly projecting bail 59 by which it may be removed from the well by the use of suitable tools. In this form, as in the form previously 45 explained, I depend upon the inward pressure against the walls of the plunger 51 to expand it and make a tight fit with the barrel 50.

In the form of the invention shown in Fig. 5 I utilize a hollow plunger 70 threaded at 71 for the reception of a quill 72. Sucker rods 73 are secured in the quill. Openings 74 are provided in the quill 72 through which oil may pass upwardly. A 55 ball 75 seats at 76, closing an opening 77 through the plunger on the up stroke. In this form I also depend upon the expansion of the plunger under pressure to maintain a tight fit.

60 In the form of the invention shown in Fig. 6 I utilize a pump rod 90 having a rigid seat 91 on the bottom thereof, and having an intermediate seat 92 free to slide thereon and held in an upper position by a spring 93. The seat 91 is arranged to

seat upon a projection 94 at the bottom of the plunger 95 and the seat 92 seats upon a projection 96 intermediate of the plunger 95. Thin cups 98 are provided, being secured to the plunger 95 at the points 100, 70 preferably by being welded to the plunger. Openings 101 and 102 are provided in the walls of the plunger communicating with the space inside the cups 98. On the up stroke of the pump rod 90 the valves 91 75 and 92 close, thus causing pressure to be exerted through the openings 101 and 102 on the interior of the steel cups 98. These cups are thus expanded against the walls 80 of the barrel in which the plunger is reciprocated. Here again I depend upon the outwardly exerted pressure to cause the 85 cups 98 to make a tight closure with the inner walls of the pump barrel.

I claim as my invention:

1. In a pump, the combination of: a pump barrel; a hollow metallic piston sliding in said pump barrel; and valve means for interrupting the flow of liquid through said piston in such a manner as to allow 90 the pressure built up by the pump to expand the hollow piston to a close sliding fit inside the cylinder, said piston having a circularly continuous one piece imperforate metallic wall portion engaging the pump 95 barrel and devoid of slits and being of suitable metal and proper proportions to so expand under said pressure.

2. In a pump, the combination of: a pump barrel; a hollow metallic piston sliding in said pump barrel; and valve means for interrupting the flow of liquid through said piston in such a manner as to allow 100 the pressure built up by the pump to expand the hollow piston to a close sliding fit inside the cylinder, said piston having a circularly continuous one piece imperforate metallic wall portion engaging the pump barrel and devoid of slits and being of suitable metal and proper proportions to 105 expand beyond the elastic limit of the metal therein under said pressure.

3. In a pump, the combination of: a pump barrel; a hollow metallic piston sliding in said pump barrel; and valve means 115 closing the bottom of the opening in said piston so as to allow the pressure built up by the pump to expand the hollow piston to a close sliding fit inside the cylinder, said piston having a circularly continuous one piece imperforate metallic wall portion 120 engaging the pump barrel and devoid of slits and being of suitable metal and proper proportions to so expand under said pressure.

4. In a pump, the combination of: a pump barrel; a hollow metallic piston sliding in said pump barrel; and valve means closing the bottom of the opening in said 130 piston so as to allow the pressure built

up by the pump to expand the hollow piston to a close sliding fit inside the cylinder, said piston having a circularly continuous one piece imperforate metallic wall portion 5 engaging the pump barrel and devoid of slits and being of suitable metal and proper proportions to be stretched beyond the elas-

tic limit of the metal therein under said pressure.

In testimony whereof, I have hereunto 10 set my hand at Los Angeles, California, this 4th day of December, 1923.

JOHN A. ZUBLIN.
